Genus and species: *Humulus lupulus* L.
Variety denomination: 'IH101033'.

BACKGROUND

The present disclosure comprises a new and distinct cultivar of *Humulus lupulus* L., and hereinafter referred to by the cultivar name 'IH101033'.

The new hop plant resulted from a planned breeding program from crossing *Humulus lupulus* 'Sterling' (un-patented) as the female parent to the male parent *Humulus lupulus* '64035M', an unpatented hop male genotype released by the USDA-ARS hop breeding and genetics program based in Corvallis, Oreg. in 1985. The resulting hop plant was selected when growing in a greenhouse in Corvallis, Oreg. during February 2011.

SUMMARY

In July 2010, a cross was made between the female hop cultivar 'Sterling' and the male hop '64035M' near Corvallis, Oreg. (FIG. 1). Both parents are publicly available genotypes released by the USDA-ARS hop breeding program located near Corvallis (Haunold et al., 1985, Registration of USDA 64035M male hop germplasm. Crop Sci. 25:889-890; Henning and Haunold, 1999, Notice of release of 'Sterling', a high-yielding Saazer-type hop cultivar. United States Dept. of Agriculture, Washington, D.C.). Seed

(57) **ABSTRACT**

A new and distinct hop plant cultivar named 'IH101033' is disclosed, characterized by having an early maturity date in Oregon's Willamette Valley; tolerance to downy mildew (*Pseudoperonospora humuli* [Miyabe & Takah.] G. W. Wilson); vigor with potentially high yield; low alpha acids content; typically high beta acids content; low total essential oil content; and unique amounts of 19 essential oil components implicated in beer flavor and aroma.

4 Drawing Sheets

2

was collected by hand, stratified at 34° F. for eight weeks, and planted into flats containing a standard soil mix in a greenhouse in Corvallis, Oreg. during January 2011. Established hop seedlings were evaluated for powdery mildew

5 (*Podosphaera macularis* [Walk.] U. Braun & S. Takam) resistance and general vigor, and 'IH101033' was one of the seedlings selected and transplanted into 1-gallon pots. Once established, potted plants were subsequently transplanted into a field nursery near Corvallis, Oreg. during May 2011 10 and given a 4' bamboo stake to climb on during that growing season. 'IH101033' was evaluated for downy mildew (*Pseudoperonospora humuli* [Miyabe & Takah.] G. W. Wilson) and powdery mildew during 2012, 2013, 2014, and 2015 at Corvallis. Due to transient outbreaks, 'IH101033' was 15 evaluated for hop looper (*Hypnea humuli* Harris) damage in 2013 and 2014 and Damson hop aphid (*Phorodon humuli* Schrank) damage in 2014. The sex of this genotype was determined to be female in 2012. Yield potential and preliminary sensory evaluations were initially evaluated in 20 2014 and 2015 when the single plant was harvested.

Based upon agronomic performance and the initial sensory assessment, 'IH101033' was propagated via rhizomes obtained from the individual mother plant in February 2015 25 with additional propagation from stem cuttings in a greenhouse. Plants were established in 1-gallon pots and transplanted into replicated field nurseries on two commercial hop farms in Oregon's Willamette Valley during the summer of 2015. These nurseries were managed by the two farms

using their normal hop production techniques. Due to the growers utilizing aggressive pest and pathogen control measures, only yield, chemistry, and sensory data were collected from these plots for 2017, 2019, 2020, and 2021. Beginning in September 2017, 'IH101033' entered into sensory evaluations by small, organized groups of craft brewers, primarily in the U.S. Pacific Northwest, although select breweries outside this region were also used. Sensory analysis consisted primarily of dry-rub evaluations, along with the hops "dry hopped" into beer at a small bench top scale using a commercial Kolsch style beer that is balanced with hop bitterness but has no hop aroma or flavor, thus allowing the hops from 'IH101033' to impart their unique aroma and flavor characteristics into the beer for sensory evaluation. Small scale pilot brews by breweries were also used to evaluate the hop character when used not only in dry-hopping, but also on the "hot side" of the brewing process.

In 2019, 'IH101033' was propagated and established in a 3.7 acre block near Silverton, Oreg., and a 6 acre block near Independence, Oreg. These blocks were managed and harvested by the two cooperating hop growers. A test crop was produced from each plot in 2020 and 2021, processed by a hop merchant in Portland, Oreg., and 96 craft brewers have created test beers to evaluate hop aroma and flavor profiles from 'IH101033' hops over a wide range of brewing styles.

The 'IH101033' hop variety is distinguished from other hop varieties due to the following unique combination of agronomic and chemical characteristics. When grown in Oregon's Willamette Valley, 'IH101033' is:

1. slightly early to mature (August 22-24);
2. tolerant of downy mildew;
3. vigorous with potentially high yield (Table 1);
4. has low alpha acids content (Tables 2, 3, 4);
5. typically has high beta acids (Tables 2, 3, 4);
6. has low total essential oil content (Tables 2, 3, 4); and
7. contains unique amounts of 19 essential oil components implicated in beer flavor and aroma (Tables 5, 6, 7).

Asexual reproduction of the new hop variety 'IH101033' was first performed in Corvallis, Oreg. via rhizomes in 2015. Subsequent propagations have been via rhizomes and stem cuttings, and this variety has remained genetically stable.

BRIEF DESCRIPTION OF THE DRAWINGS

FIG. 1 illustrates the pedigree for 'IH101033'.

FIG. 2 shows the typical 3-lobe and 5-lobe shapes of mature leaves of 'IH101033'.

FIG. 3 shows the cordate shape of an immature leaf of 'IH101033'.

FIG. 4 shows typical hop cones for 'IH101033'.

DETAILED BOTANICAL DESCRIPTION

The following detailed description of the 'IH101033' variety is based on observations of various 2-6-year old plants, 2nd propagation generation, growing on a commercial hop farm in the Willamette Valley of Oregon between 2017 and 2021. The plants were 2 years old when first evaluated in 2017, and 6 years old by 2021. The original plant has been observed growing in a cultivated area in Corvallis, Oreg. The new cultivar has not been evaluated under all possible environmental conditions but was developed for Oregon's Willamette Valley (USDA hardiness zone 8b near 45 degrees North latitude). Certain characteristics of this variety, such as growth and color, may change with changing environmental conditions (e.g., light, temperature,

moisture, nutrient availability, or other factors). The color descriptions are all based on *The Royal Horticultural Society Colour Chart*, 6th edition, 2015.

Parentage:

Female parent.—*Humulus lupulus* 'Sterling'.

Male parent.—*Humulus lupulus* '64035M'.

COMPARISON TO FEMALE PARENT AND OTHER COMMERCIALLY AVAILABLE VARIETIES

Tables 1-7 below provide comparisons between various traits of the 'IH101033' variety, the female parent 'Sterling', the standard Oregon aroma hop cultivar 'Cascade' (unpatented), and 'OR91331' (U.S. Plant Pat. No. 31,042). As shown in Table 1, 'IH101033' is vigorous with potentially higher yield than 'Sterling', 'Cascade', and 'OR91331'.

TABLE 1

Per-plant yield for 'IH101033' over four years at a commercial hop farm in the Willamette Valley of Oregon.		
Genotype	Yield (lbs) [†]	Range (lbs)
2017		
'IH101033'	9.37 a	3.40-8.24
'Sterling'	6.18 ab	5.41-7.68
'Cascade'	5.30 b	7.16-12.60
2019		
'OR91331'	11.67 a	8.65-17.30
'IH101033'	11.65 a	9.91-13.36
'Sterling'	8.73 a	6.75-10.35
'Cascade'	8.06 a	6.15-12.40
2020		
'IH101033'	15.59 a	12.70-16.70
'Sterling'	12.33 b	9.80-13.50
'OR91331'	8.55 c	6.95-10.20
2021		
'IH101033'	12.58 a	11.15-13.50
'Sterling'	10.06 ab	6.80-14.10
'OR91331'	8.78 b	7.75-9.65

[†]Means within a year followed by the same letter are not statistically significant at P = 0.05.

As shown in Tables 2-4 below, 'IH101033' has lower alpha acids content than 'Cascade' and 'OR91331', and occasionally lower than 'Sterling'. Tables 2-4 also show that 'IH101033' typically has higher beta acids than 'Cascade', 'OR91331', and 'Sterling', and has lower total essential oil content than 'OR91331', but similar to 'Sterling' and 'Cascade'.

SUMMARY OF MORPHOLOGICAL TRAITS

Tables 8, 9, and 10 summarize the principal morphological characteristics of 'IH101033' and how they may differ from 'Sterling' (female parent) and the standard Oregon aroma hop cultivar 'Cascade'. When grown in Oregon's Willamette Valley, 'IH101033':

1. has a wider cone than 'Cascade' (Table 8);
2. has narrower and shorter bracts than the female parent 'Sterling', and shorter bracts than 'Cascade' (Table 8);
3. has shorter and wider bracteoles than 'Sterling' and 'Cascade' (Table 8);
4. has longer mid-canopy main bine internode length than 'Cascade' and 'Sterling' (Table 9); and

5. has a longer and wider leaf than 'Sterling' and 'Cascade' (Table 9).

Additional morphological characteristics are presented in Table 10, while characteristic leaf and cone shapes are presented in FIGS. 2-4. 'IH101033' is slightly earlier to mature (August 22-24) than the female parent 'Sterling' (August 30-September 1), and earlier than 'Cascade' (September 1-5). In addition, 'IH101033' is tolerant of downy mildew (similar to 'Sterling') where 'Cascade' and 'OR91331' are considered resistant.

TABLE 8

15 Cone measurements for 'IH101033', its female parent 'Sterling', and an industry-standard aroma hop cultivar 'Cascade' when grown in Oregon's Willamette Valley.

Genotype	Trait	Range
'Sterling'	Cone Bract Width (cm)	
	'Sterling'	1.19 a
	'Cascade'	1.16 a
'IH101033'	'IH101033'	1.04 b

TABLE 9-continued

Morphological measurements for 'IH101033' and two additional aroma hop genotypes grown in the Oregon's Willamette Valley.		
Genotype	Trait	Range
<u>Leaf Length (cm)</u>		
'IH101033'	16.47 a	13.60-19.10
'Cascade'	14.11 b	12.70-16.00
'Sterling'	13.45 b	10.50-15.10
<u>Sidearm Length (cm)</u>		
'Cascade'	78.95 a	51.10-129.50
'IH101033'	74.96 a	55.80-94.20
'Sterling'	59.12 a	32.10-104.50
<u>Sidearm Internode Length (cm)</u>		
'IH101033'	9.38 a	6.50-13.50
'Cascade'	8.65 a	3.10-15.80
'Sterling'	7.70 a	3.60-14.30

TABLE 10

Morphological characteristics for the hop genotype 'IH101033' when grown in Oregon's Willamette Valley.	
Trait	Descriptor
Ploidy	2X (diploid)
Plant	Vigorous climbing bine
Shape	Columnar
Plant head volume	High
Target area	Oregon's Willamette Valley (USDA hardiness zone 8b near latitude 45 degree North)
<u>Bine</u>	
Color	145D
Anthocyanin coloration	184C
Mid-canopy internode Length (cm)	Average = 24.46, Range = 20.0-28.2
Diameter (mm)	Average = 7.2, Range = 5.0-9.0
Total Length (ft)	21
Sidearm	
Mid-canopy length	Medium (55.8-94.2 cm)
Petiole	
Length (cm)	Average = 8.0, Range = 6.8-11.5
Color	181A top, N144C bottom
Shape	Flat upper surface with channel
Leaf	
Arrangement	Opposite
Shape	Immature = cordate, mature = mix of 3-lobed and 5-lobed
Adaxial leaf texture	pubescent
Abaxial leaf texture	pubescent, particularly along veins
Color	Upper = NN137A, lower = NN137D
Mature leaf width (cm)	Average = 15.44, Range = 11.5-17.5
Mature leaf length (cm)	Average = 16.47, Range = 13.6-19.1
Leaf lobing	Immature = cordate, mature = mix of 3-lobed and 5-lobed
Venation	primary order: palmate secondary order: craspedodromous
Vein color	Upper = 146A, lower = 146B
Blistering	Absent
Leaf margin	Serrated
Lateral length, mid-canopy (cm)	Average = 74.96, Range = 55.8-94.2

TABLE 10-continued

Morphological characteristics for the hop genotype 'IH101033' when grown in Oregon's Willamette Valley.	
Trait	Descriptor
Lateral internode length (cm)	Average = 9.38, Range = 6.5-13.5
Blistering Cone	None
Shape	Medium ovate
Flowering date	July 10-20
Maturity date	August 22-24
Coning abundance	Mid-canopy cone number: Many Upper-canopy cone number: Many
Length (cm)	Average = 4.10, Range = 3.0-5.2
Width (cm)	Average = 2.17, Range = 1.8-2.9
Number of bracts per cone	Average = 29.2, Range = 22-36
Number of bracteoles per cone	Average = 48.5, Range = 40-60
Total bracts + bracteoles per cone	Average = 77.7, Range = 62-96
Bract color	145A
Bract length (cm)	Average = 1.63, Range = 1.0-2.0
Bract width (cm)	Average = 1.04, Range = 0.2-1.2
Bract apex length (mm)	Average = 2.03, Range = 1.0-3.0
Bracteole length (cm)	Average = 0.89, Range = 0.7-1.0
Bracteole width (cm)	Average = 1.52, Range = 1.3-1.8
Bracteole color	145A

COMPARISON TO MALE PARENT '64035M'

The male parent, '64035M', was released by the USDA in 1984 as a downy mildew-resistant male genotype for breeding purposes. It derives from open-pollinated seed collected off of the German female hop 7K491 at Wye College, England. Key differences between 'IH101033' and its' male parent '64035M' include:

1. 'IH101033' is a female genotype and only produces female flowers while '64035M' is a male genotype and only produces male flowers
2. 'IH101033' is tolerant of downy mildew while '64035M' is considered resistant.

SENSORY OBSERVATIONS

Beginning in September 2017, sensory evaluations by small, organized groups of craft brewers were initiated. To date, 96 brewers have participated in dry-rub evaluations and small-scale test beers in which 'IH101033' was dosed into a Kolsch-style beer that has no aroma or flavor characteristics. Small-scale test beers were also produced to assess 'IH101033' character on both the hot-side and dry-hopping stage. Typically, the first notes noticed are the citrus notes lemon supported by lime. Brewers report that the initial lemon and lime notes are followed by fresh melon notes (usually honeydew and cantaloupe) and mixed wild-flower floral notes. Additional notes reported include dry grass and cinnamon or baker's spice.

I claim:

1. A new and distinct variety of hop plant named 'IH101033', substantially as illustrated and described herein.
